UNITED STATES PATENT OFFICE.

HENRY W. ROOS, OF CINCINNATI, OHIO, AND EARL R. BELL, OF COVINGTON, KENTUCKY,
ASSIGNORS, BY DIRECT AND MESNE ASSIGNMENTS, OF SIXTY-FIVE ONE-HUN-
DREDTHS TO SAID ROOS AND THIRTY-FIVE ONE-HUNDREDTHS TO GEORGE W.
MEYER, OF CINCINNATI, OHIO.

ADJUSTABLE SHORE.

1,195,503.

Specification of Letters Patent. Patented Aug. 22, 1916.

Application filed July 20, 1914. Serial No. 851,881.

To all whom it may concern:

Be it known that we, HENRY W. ROOS, of Cincinnati, in the county of Hamilton, in the State of Ohio, and EARL R. BELL, of Covington, in the county of Kenton, in the State of Kentucky, have invented certain new and useful Improvements in Adjustable Shores; and we do hereby declare the following to be a full, clear, and exact description of the same, reference being had to the accompanying drawings, forming a part of this specification, and to the reference-numerals marked thereon.

Our invention relates to adjustable shores for use in connection with concrete structures and the like, the purpose being to provide a simply constructed device that can be economically made for supporting concrete forms, such as girder, beam and floor forms, until the composition material within the forms has thoroughly dried and hardened, and for any other purpose where shoring is necessary.

A further purpose of the invention is to provide a device that is readily adjustable as to size in order to support forms at different elevations, and which, when adjusted, will support the load firmly, the parts being so arranged that the gripping action of the adjustable parts, one upon the other, increases in proportion to the load put upon the device.

To these and other ends the invention consists in certain improvements and combinations of parts all as will be hereinafter more fully described, the novel features being pointed out in the claims at the end of the specification.

In the drawings: Figure 1 is a front elevation of a construction showing a preferred embodiment of the invention; Fig. 2 is a side view, and Fig. 3 is a horizontal section on the line 3^a-3^a of Fig. 1.

Similar reference characters in the several figures indicate the same parts.

According to the present embodiment, which illustrates a preferred method of carrying out the invention, we employ a pair of relatively movable members, which can be adjusted with relation to each other and securely retained in such adjusted relation, the lower member resting upon a floor or other

support while the upper member engages the form or structure to be supported.

The lower member preferably comprises a post A adapted to rest upon the floor, as shown in Figs. 1 and 2. The post A is provided with an enlarged upper end, which may be formed by securing blocks B to the opposite sides thereof. C designates strips or bars which are suitably secured to opposite sides of the member A, and extend beyond the blocks B, forming recesses or guideways for the upper member, which is now to be described.

The upper member includes a horizontal or supporting portion D, to which are connected vertical portions or legs E, the latter being held in proper relation to the horizontal portion by means of the attaching straps F. The legs E are adapted to engage the blocks B of the lower member, being movable between the end portions of the strips C, which thereby serve as centering guides to retain the upper member in its proper relation to the lower member.

The relatively movable members are held in their adjusted relation by means of clamping devices carried by the legs E, and engaging the post A. To this end, we employ a pair of clamping yokes, one pivoted upon each leg E, the yokes being designated at G. The clamping yokes G are also pivotally connected to each other at H, and include clamping portions or jaws I which engage opposite sides of the post A in the manner shown in Figs. 1 and 3. The clamping yokes are preferably of equal size and are attached, as shown in Fig. 3, a spacing block or washer J being employed between the legs E and the adjacent walls of the clamping yokes.

In the application of the shore, the device is positioned on the floor beneath a form to be supported, and the upper member is then elevated until it comes into engagement with said form. It will be seen that in separating the parts, the clamping devices recede from the post A, but when pressure is applied upon the upper member downwardly, it causes the clamping yokes to move inwardly against the opposite sides of the post A, and to grip the same. The greater the load that is applied, correspondingly tighter

will be the gripping action of the clamping yokes, so that the parts are securely retained in their adjusted relation as long as any application of pressure continues.

We claim as our invention:

1. An adjustable shore comprising a pair of relatively movable members, and a pair of clamping yokes pivoted to one of said members, said yokes being pivotally connected to each other and having engagement with opposite sides of the other of said members.
2. An adjustable shore comprising a lower

member in the form of a post, an upper member movable relatively to the lower member and including a pair of legs arranged on opposite sides of said post, and a clamping yoke pivoted to each of said legs, the clamping yokes being pivotally connected to each other and engaging opposite sides of the post.

HENRY W. ROOS.
EARL R. BELL.
